UNITED STATES PATENT OFFICE

158,422

COMBINED PINCUSHION AND RECEPTACLE

Bernard Ulvad, Leominster, Mass., assignor to
Foster Grant Co., Inc., Leominster, Mass., a corporation of Massachusetts

Application May 11, 1949, Serial No. 2,573

Term of patent 14 years

(Cl. D3—19)

To all whom it may concern:

Be it known, that I, Bernard Ulvad, a citizen of the United States, residing at Leominster, Worcester County and State of Massachusetts, have invented a new, original, and ornamental Design for a Combined Pincushion and Receptacle, of which the following is a specification, reference being had to the accompanying drawings, forming a part thereof, in which:

Fig. 1 is an exploded view in elevation of a combined pincushion and receptacle, showing my new design;

Fig. 2 is a top view of the lid and pincushion, with a part of the latter broken away and sectioned to indicate foam rubber or like soft substance into which pins can be stuck;

Fig. 3 is an inside view of the lid;

Fig. 4 is a view of the interior of the receptacle, with the lid removed; and,

Fig. 5 is a bottom view of the receptacle.

I claim:

The ornamental design for a combined pincushion and receptacle, substantially as shown and described.

BERNARD ULVAD.
